[57] ABSTRACT

A finger operated dispenser for use with a pressurized container including an annular shoulder, an adapter detachably secured to said annular shoulder, an elongated tube connected to said adapter and said dispenser whereby the user may control the discharge of material from said container at a remote location.

FIG. 5

DISPENSER FOR PRESSURIZED CONTAINER

BACKGROUND OF THE INVENTION

At the present time, pressurized containers of medicinal preparations, hair spray, paint or other liquids are commercially available. The size and weight of such containers as well as the dispensing means associated therewith makes it inconvenient to apply said liquid in an exact, predetermined location.

SUMMARY OF THE INVENTION

This invention relates to an improved, finger operated dispenser for use with pressurized containers of liquids. An adapter, detachably secured to any currently available pressurized container, includes means coacting with the valve mechanism in said container. An elongated tube connects to said adapter and to a normally closed valve in said dispenser. A rotatable disc on said dispenser includes a plurality of nozzles whereby the user may select a desired spray pattern for use with the object which is to be coated.

BRIEF DESCRIPTION OF THE DRAWINGS

FIG. 1 is a fragmentary, side elevational view, partly broken away and partly in section, of the dispenser of the subject invention.

FIG. 2 is a greatly enlarged, vertical sectional view through the foremost portion of the dispenser along the longitudinal axis thereof with the valve in open condition.

FIG. 3 is a greatly enlarged, front elevational view of one embodiment of dispenser head utilized in the practice of the invention.

FIG. 4 is a greatly enlarged, vertical sectional view along the longitudinal axis of another embodiment of dispenser head, showing the valve in closed condition.

FIG. 5 is a greatly enlarged, vertical sectional view along the longitudinal axis of the adapter of the invention.

FIG. 6 is a greatly enlarged, horizontal sectional view taken slightly above the plane of the lever of the adapter, looking downwardly.

Referring now to the drawings, wherein like reference characters designate like or corresponding parts throughout the several views, there is shown in FIGS. 1 and 5 of the drawings a conventional pressurized container 10 including annular shoulder 11 in the upper end thereof which defines depression 12; upwardly extending bell portion 13 in the center of said depression accommodates dispensing valve 14 with stem 15 and vertical dispensing opening 16 extending above the plane of shoulder 11. In the pressurized container thus formed, stem 15 is normally biased upwardly as by a suitable spring; when said stem is depressed against the pressure of said spring, the material from container 10 flows through opening 16.

As best seen in FIG. 5 of the drawings, adapter 17 is detachably secured to shoulder 11 of container 10. More specifically, longitudinally extending body 18 terminates downwardly in ring 19 which defines recess 20; said ring is adapted to pass intermediate annular shoulder 11 and bell portion 13. Male threads 21 are provided above ring 19 exteriorly of the lower portion of body 18; said threads terminate upwardly in proximity to collar 22 integrally formed with said body and slightly below the midpoint thereof. Nut 23, mating with threads 21, terminates downwardly in collar 24 of

reduced diameter provided exteriorly with laterally extending arcuate member 25 adapted to pass downwardly and inwardly of shoulder 11 thereby engaging the same, and exteriorly in downwardly depending lip 26 adapted to frictionally engage the outer surface of ring 19.

Upwardly of collar 22, cylindrical section 27 of said body is of reduced diameter with integrally formed, laterally extending, generally U-shaped lugs 28-29 (see FIG. 6) in proximity to the upper end thereof. Vertically extending gussets 30 support the lower portion of said cylindrical section. Actuating lever 31 includes outwardly extending trunnions 32-33 adapted to insert into lugs 28-29 and essentially perpendicularly extending arm 34 the innermost end of which is provided with transversely extending teeth 35. Downwardly of trunnions 32,33 said lever includes an integrally formed, inwardly extending, arcuate spring 36 the lower end of which bears against cylindrical section 27. Longitudinally extending bore 37 in body 18 communicates upwardly with opening 38 in the top of said body.

Still referring to FIG. 5 of the drawings, sleeve 38 inserts into the lower portion of bore 37; said sleeve terminates downwardly in diverging conical section 40 the inner surface of which is adapted to bear against bell portion 13 with the lower edge of said conical section 40 normally lying in the plane of the lower edge of ring 19. As will hereinafter be described, ring 41 may be carried on sleeve 39 whereby said sleeve may be adjustably positioned within bore 37 to accommodate bell portion 13 of any height. Elongated valve 42 terminates downwardly in integrally formed and diverging conical section 43; longitudinally extending tube 44 of metallic composition, adapted to insert into opening 16, is fixedly secured in valve 42 with the lower end thereof extending substantially downwardly of the lower edge of conical section 43. Spring 45, carried on valve 42, bears against the upper end of sleeve 39 and the lower end of collar 46 integrally formed in the approximate medial portion of said valve, respectively. Upwardly of collar 46, generally cylindrical section 47 of said valve is adapted to pass through opening 38.

As best seen in FIG. 6 of the drawings, a plurality of longitudinally spaced teeth 48 are provided in section 47 intermediate lugs 28-29, said teeth are adapted to be engaged by teeth 35 on lever 31. The upper end of valve 42 is threaded and preferably beveled, indicated by reference numerals 49-50, respectively. One end of an elongated tube 51 of plastic composition is press fitted over bevel 50 and fixedly secured thereto by means of nut 52 adjusted to bear against the outer surface thereof. The lower end of tube 44 is desirably provided with a diagonally and upwardly extending vent or recess 53; bore 54 of tube 44 communicates with bore 55 of corresponding diameter in said valve downwardly of collar 46 with coaxial bore 56 of greater diameter communicating therewith and surfacing in the top of said valve.

Referring now to FIGS. 1-4 of the drawings, there is shown a finger actuated dispenser 57 detachably secured to the remote end of elongated tube 51. More specifically, dispenser 57 includes a generally cylindrical forward section 58 which terminates rearwardly in male threads 59; rearwardly converging base 60 includes a longitudinally extending recess 61 in the foremost end thereof and female threads 62 adapted to en-

gage threads 59. Valve 63 is adjustably mounted in longitudinally extending bore 64 in forward section 58.

Forwardly, bore 64 includes converging conical shoulder 65, communicating bore 66 of reduced diameter, converging shoulder 67, converging conical seat 68 paralleling shoulder 67 and rearwardly thereof, and axial bore 69 of still further reduced diameter. Valve 63 includes integrally formed, diverging conical section 70 the circumferential edge of which is adapted to expand against bore 64 in a tight fit when liquid under pressure is introduced into the said bore in a manner hereinafter to be described. Forwardly thereof, valve 63 includes a reduced diametral cylindrical section 71, and a still further reduced diametral cylindrical section 72 which terminates forwardly in converging conical face 73 adapted to bear against seat 68.

Exteriorly, forward section 58 terminates rearwardly in transversely spaced, U-shaped lugs 74-75 (lug 74 not shown) with recess 76 therebetween. Forwardly extending lever arm 77 includes trunnions 78-79 (trunnion 79 not shown) adapted to insert into lugs 74,75; essentially perpendicularly extending leg 80 of lever 77 inserts downwardly into recess 81 provided in valve 63. Spring 82 carried in recess 61 bears against the rear end of valve 63 maintaining the same in normally closed condition. Downwardly depending connector 83, integrally formed on forward section 58, includes male threads 84 and desirably is beveled, indicated by reference numeral 85. The remote end of tube 51 is press fitted onto bevel 85 and retained thereon by means of nut 86 adjusted to bear against the outer surface of said tube. Axial bore 87 in connector 83 communicated with bore 64 forwardly of the foremost limit of travel of valve 63.

Disc 88 terminates forwardly in transversely extending collar 89; female threaded portion 90, provided in the rear surface of said disc, is adapted to mate with threads 91 in the foremost end of section 58. Bore 92 in disc 88 communicates with bore 69 heretofore mentioned.

Rotatable disc 93 includes a plurality of integrally formed and rearwardly extending lugs 94 adapted to pass laterally of collar 89 with perpendicularly depending flanges 95 on each lug passing rearwardly of said collar. As viewed in FIG. 3, a plurality of nozzles 96-99 to provide sufficient spray patterns are press fitted or otherwise secured in disc 93 in such a manner that each of said nozzles is adapted to align with bore 92 in disc 88. Projections 100 on the rear surface of disc 93 insert into depressions 101 in the foremost surface of disc 88 for such alignment.

In the embodiment of FIG. 4, a single nozzle 102 of generally truncated conical configuration terminates rearwardly in female threads 103 adapted to engage threads 91 on section 58 with axial bore 104 in said nozzle communicating with bore 69.

In use, nut 23 is at least partially threaded onto threads 21 and collar 24 inserted intermediate shoulder 11 and bell portion 13; nut 23 is then rotated in such a direction that arcuate member 25 passes under and engages shoulder 11 of container 10, and conical section 40 bears against bell portion 13 of said container. A downward force on section 47 causes tube 44 to insert into opening 16 in stem 15. The user may conveniently grasp dispenser 57 with the fingers and apply a downward force on lever 77 whereby the material in container 10 is dispensed through a selected nozzle.

Upon releasing lever 77, valve 63 returns to normally closed condition; upon depressing lever 31, spring 45 forces valve 42 upwardly whereby tube 44 is withdrawn from stem 15.

It is understood, of course, that the foregoing disclosure relates to only preferred embodiments of the invention and that it is intended to cover all changes and modifications of the examples of the invention herein chosen for the purpose of the disclosure which do not constitute departures from the spirit and scope of the invention.

What is claimed is:

1. A dispenser adapted to coact with a pressurized container of liquid, said container including an annular shoulder, valve mechanism and valve stem, comprising an adapter terminating downwardly in a ring, said adapter including adjustable means adapted to engage said shoulder, said adjustable means passing intermediate said ring and said shoulder, a sleeve carried in said adapter, said sleeve terminating downwardly in a diverging conical section, said sleeve carrying a valve, said valve adapted to insert into said valve stem, an elongated tube connected at one end to said adapter, a dispenser, a valve slidably mounted in said dispenser, said elongated tube connected to said dispenser forwardly of said valve, at least one nozzle in said dispenser, and manually operable means to control the flow of liquid from said container.

2. The invention of claim 1 wherein said valve in said dispenser terminates forwardly in a diverging conical section adapted to expand under pressure.

3. A dispenser adapted to coact with a pressurized container of liquid, said container including an annular shoulder, a valve mechanism and valve stem, comprising

an adapter terminating downwardly in a ring, said adapter including adjustable means adapted to pass intermediate said ring and said annular shoulder, a dispenser, a valve slidably mounted in said dispenser, said valve terminating forwardly in a diverging conical section adapted to expand under pressure, said adapter connected to said dispenser forwardly of said valve in said dispenser, at least one nozzle in said dispenser, and means in said dispenser coacting with said valve to control the flow of liquid from said container.

4. The invention of claim 1 further including means on said adapter to retain said valve in said adapter in said valve stem of said container.

5. The invention of claim 1 further including means coacting with said adapter to maintain said valve of said adapter in said valve stem of said container.

6. The invention of claim 3 wherein said adapter includes means to retain said valve of said adapter in said valve stem of said container.

7. A dispenser adapted to coact with a pressurized container of liquid, said container including an annular shoulder, a valve mechanism and valve stem, comprising

an adapter including an externally threaded portion, a nut carried on said threaded portion, said nut terminating downwardly in a shaped portion adapted to engage said shoulder of said container, a sleeve carried in said adapter, said sleeve terminating downwardly in a diverging conical section, said sleeve carrying a valve, said valve adapted to insert into said valve stem of said container, a dispenser, a valve slidably mounted in said dispenser, said adapter connected to said dispenser, at least one nozzle in said dispenser, and

manually operable means to control the flow of liquid from said container.

8. The invention of claim 7 wherein said valve in said dispenser terminates forwardly in a diverging conical section adapted to expand under pressure.

9. The invention of claim 7 further including means on said adapter to maintain said valve in said adapter in said valve of said container.

10. The invention of claim 7 wherein said valve in said adapter is normally biased upwardly, said adapter including means to secure said valve in said valve stem when said valve is depressed.
